DESIGN FOR A TOY BALLOON OR SIMILAR ARTICLE

David B. van Dam, Brooklyn, N. Y.

Application May 20, 1941, Serial No. 101,031

Term of patent 3½ years

To all whom it may concern:

Be it known that I, David B. van Dam, a citizen of the Netherlands, residing at Brooklyn, in the county Kings and State of New York, have invented a new, original, and ornamental Design for a Toy Balloon or Similar Article, of which the following is a specification, reference being had to the accompanying drawing, forming part thereof.

In the drawing

Fig. 1 is a view in elevation of a toy balloon looking at same from one side showing my new design; and

Fig. 2 is a similar view looking from the opposite side thereof.

The design consists essentially of the representation of clouds upon the surface of the balloon and cherubs associated with the clouds.

I claim:

The ornamental design for a toy balloon or similar article, substantially as shown and described.

DAVID B. VAN DAM.
